UNITED STATES PATENT OFFICE.

HENDRICK W. LUNDQUIST, OF SAN DIEGO, CALIFORNIA.

AUTOMATIC ADVERTISING-MACHINE.

1,399,438.

Specification of Letters Patent.

Patented Dec. 6, 1921.

Application filed February 20, 1918. Serial No. 218,251.

To all whom it may concern:

Be it known that I, HENDRICK W. LUNDQUIST, a citizen of the United States, residing at San Diego, in the county of San Diego 5 and State of California, have invented certain new and useful Improvements in Automatic Advertising-Machines, of which the following is a specification.

My invention relates to a machine for 10 automatically controlling, operating and lighting advertising cards, and for reproducing the same on a screen consisting of a translucent glass plate which is a portion of the machine, and:

15 The objects of my invention are: First, to provide automatic means for changing the cards in their proper sequence, thus providing an automatically operated advertising machine: second, to provide a machine 20 of this class in which the cards may be shown either on one side of the machine or on opposite sides as desired: third, to provide a machine of this class in which a plurality of different cards may be shown in proper 25 sequence as desired: fourth, to provide a machine of this class in which the advertising may be shown in the day time as well as at night, without darkening the surroundings: fifth, to provide a machine of this class 30 the operation and maintenance of which are very inexpensive, and sixth, to provide a machine of this class which is simple, economical of construction, durable, readily installed in places where it is desired to use 35 the machine and will not readily deteriorate or get out of order.

With these and other objects in view as will appear hereinafter, my invention consists of certain novel features of construction, combination and arrangement of parts 40 as will be hereinafter described in detail and particularly set forth in the appended claims, reference being had to the accompanying drawings and to the characters of 45 reference thereon which form a part of this specification, in which:

Figure 1 is a longitudinal sectional view of the casing in the preferred form and showing the inner working parts in elevation to facilitate the illustration. Fig. 2 is a fragmentary sectional view through 2-2 of Fig. 1. Fig. 3 is a fragmentary transverse sectional view through 3-3 of Fig. 1 and showing the operating parts in elevation 55 to facilitate the illustration. Fig. 4 is an enlarged assembly view of some of the operating parts. Fig. 5 is a sectional view through 5-5 of Fig. 1, showing some of said working parts. Fig. 6 is a fragmentary plan view showing the modified form of construction for reproducing the card on the translucent plates, and Fig. 7 is a fragmentary sectional view through 7-7 of Fig. 6. 60

Similar characters of reference refer to similar parts throughout the several views 65 of the drawings.

The card holders 1, 2, 3 and 4; supporting bracket 5; spiders 6; illuminating chamber 7; gear 8; brake member 9; support 10; gear 11; circuit breaker 12; worm pinion 13; 70 motor 14; casing 15; hood 16; lens 17; lamps 18; support 19 and translucent plate 20, constitute the principal parts of my automatic advertising machine.

The casing 15 may be made any shape 75 or form desired and mounted on the bottom thereof in one side is the bracket 5 in which is journaled the one end of the shaft 6^a and the other end of said shaft is journaled in the partition 15^c of said casing. Mounted 80 on this shaft 6^a at each end are the spiders 6 and pivotally mounted on the outwardly extending ends of the spider arms are the card supports 1, 2, 3 and 4 which are flat members adapted for the advertising cards to rest 85 on and said cards are secured to the opposite sides of said supports. Secured on said shaft 6^a on the opposite side of the partition 15^c from the spiders 6, is a gear 8 which is provided with laterally extending lugs 8^a 90 and mounted so as to engage with the teeth of said gear 8 is the brake member 9 which is a bifurcated member actuated by means of a projecting lug 12^a on the circuit breaker 12. This circuit breaker 12 is secured on the 95 one side of the gear 11 and consists of a band an insulated lug 12^a which serves as a circuit breaker and brake release. The gear 11 is a worm gear and it is operated by means of the worm pinion 13, which is operated by 100 means of the motor 14 through belt 14^a and sheaves 14^b and 14^c. Two of the lugs 8^a on the gear wheel 8 are adapted to engage with a latch 11^a on the gear 11 with each revolution of said gear 11 as shown by solid and 105 dotted lines in Fig. 5. Mounted on this shaft 6^a is also a sprocket wheel 6^b upon which is mounted a chain 6^c shown best in Fig. 2 of the drawing, which extends to a similar sprocket and shaft which is adapted to oper- 110

ate in unison with the shaft 6 for showing the cards on opposite sides of the machine. Mounted on the casing 15 is a trip member 15^a which extends inwardly and engages the 5 card holders 1, 2, 3 and 4 as they are revolved by the spider 6 and turn them one-half revolution. This trip also serves as a stop for preventing them turning more than one-half revolution so that the cards on each 10 side are shown by turning the holders with each revolution of the spider.

It will be here noted that the lug 12^a on the circuit breaker 12 is insulated for the 15 purpose of opening and closing the circuit to the lamps 7^a in the light chamber 7 so that the lights 7^a are not on during the revolution of the spider 6 and the movement of the holders 1, 2, 3 and 4.

In the modified form of construction 20 shown in Figs. 6 and 7 of the drawings instead of the light chamber 7, there is provided a differently shaped light chamber, shaped as shown best in Figs. 6 and 7 of the drawings, forming a reflector and provided 25 with an opening in one side and the card holders 1, 2, 3 and 4 are stopped in front of this opening. It is provided with a plurality of lamps 18 therein so positioned as to throw the light backward centrally on the 30 card in the holder for illuminating the card and in said light chamber in alinement with the center of the card holder is a lens 17 and in front of the lens 17 is a translucent plate 20; these lights 18 are lighted in the same 35 manner as the lights 7^a in the chamber 7, causing an illumination of the card thus throwing the picture upon the translucent plate 20 while the card holder is in position but the lights go out with the movement of 40 said card holders.

Though I have shown and described a particular construction, combination and arrangement of parts and certain modifications thereof I do not wish to be limited to this 45 particular construction, combination and arrangement nor to the modification thereof but desire to include in the purview of my invention the construction, combination and arrangement substantially as set forth in the 50 appended claims.

It is obvious that with this construction there is provided an automatic advertising machine in which the negatives or cards are automatically moved into position and illuminated, that the motor 14 revolving the 55 worm pinion 13 will cause the gear 11 to revolve which in turn will revolve the gear 8 a partial revolution, thus turning the

spider and properly positioning the card holders.

It will be here noted that there is provided a circuit breaker 12^a for cutting off the current to the lamp 7 during the movement of gear 8 and the spider 6 which causes an intermittent lighting of the light chamber 65 there being no light during the movement of the card holders, that an enlarged reproduction of the face of the card placed into the card holder will be thrown upon the screen 20 by reason of the radiation of the 70 light from the lamp 7^a thrown upon the face of said card, then through the lens 17 and onto the screen 20 which is a translucent screen which provides for the reproduction of the cards upon the screen in day light as 75 well as in darkened surroundings, that the device as a whole is simple, economical of construction and automatic in its operation.

Having thus described my invention what I claim as new and desire to secure by Letters Patent, is:

1. In an automatic advertising machine, the combination of spaced apart spider members, card holders pivotally mounted between each two pairs of arms on said spider members, each card holder provided with oppositely disposed card supports, gear, ratchet, escapement and brake means for intermittently revolving said spider a portion of a revolution, stop means secured to the casing 85 for engaging said card holders and revolving them a one-half revolution with each revolution of said spider, means for intermittently illuminating the card on one side of said holders and means for projecting the matter 90 on said card onto a translucent plate during the time said card remains standing.

2. In an automatic advertising machine, the combination of a plurality of card holders each pivotally mounted between a pair of revolving spiders, gear, escapement and lock means for intermittently revolving said spiders, a stop means for engaging said card holders in the revolution of said spiders for revolving said card holders a one-half revolution, means for intermittently illuminating one card holder with the movement of said spider, means for locking said spider for a certain pre-determined time and means for projecting the matter on said card on to a 100 translucent plate during the time said card remains standing.

In testimony whereof, I have hereunto set my hand at San Diego, California, this seventh day of February, 1918.

HENDRICK W. LUNDQUIST.
